* cited by examiner

Primary Examiner — Ian Simmons*Assistant Examiner* — Richelle G Shelton(74) *Attorney, Agent, or Firm* — Medley, Behrens & Lewis, LLC; Nathan T. Lewis(57) **CLAIM**

The ornamental design for a display screen with a graphical user interface, as shown and described.

DESCRIPTION

The FIGURE is a front view of a display screen with a graphical user interface.

The display screen shown in an irregularly-broken line style, as well as the text and the features of the graphical user interface shown in regularly-broken lines depict unclaimed subject matter.
